UNITED STATES PATENT OFFICE.

GRAFTON E. LUCE, OF CHICAGO, ILLINOIS, ASSIGNOR, BY MESNE ASSIGNMENTS, TO
CHARLES A. BROWN, OF HINSDALE, ILLINOIS.

BURNER-NOZZLE AND CONNECTION THEREFOR.

1,286,039.

Specification of Letters Patent. Patented Nov. 26, 1918.

Application filed March 20, 1915. Serial No. 15,784.

To all whom it may concern:

Be it known that I, GRAFTON E. LUCE, a citizen of the United States, residing at Chicago, in the county of Cook and State 5 of Illinois, have invented a certain new and useful Improvement in Burner-Nozzles and Connections Therefor, of which the following is a full, clear, concise, and exact description, reference being had to the accompanying drawings, forming a part of this 10 specification.

The present invention resides in an improved burner nozzle and connection therefor. The nozzle herein described is particularly adapted for use in carrying out processes for burning brick wherein the burner nozzle is employed during the first 15 part of the operation for atomizing and projecting a spray of oil into the furnace spaces, 20 that is, the arches of the kiln and is thereafter employed in conjunction with induction pipes for injecting steam and air or other elastic fluid into the kiln.

While I have stated that the invention is 25 adapted to this particular purpose, I do not thereby intend to limit the invention to such use only as I am aware that it is capable of use in numerous other situations and relations for performing its functions.

30 The object of the present invention is to provide an improved burner nozzle. A further object is the provision of improved connection between the stationary main and the nozzle whereby adjustment and control of the nozzle may be facilitated. In the accompanying drawings which form a part of the present specification,

Figure 1 is an isometric view of the burner nozzle and connection.

40 Fig. 2 is a similar view of the inner end of the induction pipe used in connection with the nozzle.

Fig. 3 is a longitudinal section of the burner nozzle.

45 Fig. 4 is a front elevation, and Fig. 5 is a vertical cross-section on the line 5, 5, of Fig. 3.

The nozzle 1 is connected to the oil pipe 2 and to the steam pipe 3 by means of flexible 50 tubes, 4 and 5, respectively. These tubes may be of solid material, flexible in nature, or may be, as illustrated, made from spirally wound flexible tubing such as is well known in the trade. The connection of the oil pipe 55 2 with the nozzle is governed by an angle

valve 6 which is connected by a short nipple 7 to a plate or pedestal 8, attached to the top of the oil pipe by means of U-bolts 9. The plate 8 has a passage therethrough which communicates with an opening in the oil pipe to allow delivery of the oil to the burner nozzle. The steam pipe 3 is connected to the burner nozzle by a similar angle valve and connection pipe and the flexible tubes 4 and 5 are each provided at 60 their ends with couplings, preferably threaded, to secure them to the angle valve and to the burner nozzle. The nozzle 1 is provided with a steam inlet extension 10 and an oil inlet extension 11 which extensions project therefrom substantially at right angles to the axis of the burner. These extensions are connected by means of street elbows to the flexible pipes 5 and 4. The oil pipe 2 and the steam pipe 3 may be secured in any fixed relation as by means of the clamps 12 to prevent displacement during installation of the burner before the arches of a brick kiln. The flexible tubes 4 and 5 are made of sufficient length to allow 65 considerable adjustment of the burner nozzle 1 in a lateral direction. Due to the elbow connection between these flexible pipes and the burner nozzle, the nozzle may be pointed at different angles by merely turning the same on the screw threads joining the elbow with the nozzle. Vertical adjustment of the burner may be secured by bodily lifting the same or by blocking up the nozzle to the desired height. In the 70 operation of burning bricks the nozzle is first used to atomize the oil to burn the same and is thereafter used to inject steam and air into the kiln by blowing through the induction pipe, the end of which is shown in 75 Fig. 2. It can be seen that the flexible tubes 4 and 5 allow the nozzle to be raised out of the way so that the induction tube 13 may be inserted in the arch of the kiln before which the burner 1 was formerly located.

After the induction pipe 13 is put in place the nozzle 1 is lowered and is allowed to rest in the yoke 14 so that the opening in the nozzle is substantially axial with the induction tube 13. The particular construction of the burner nozzle is shown in Figs. 3, 4 and 5. The nozzle comprises essentially a steam projecting nozzle and an oil projecting nozzle combined co-axially into a single struc- 110

ture. The casing 15 is hollowed out to form a front steam space 16 and a rear space 17 and in between these two spaces, which are communicating, there is formed the oil space 18. The wall separating these spaces is pierced axially to allow the introduction of the stem 19 of the needle valve proper. The stem 19 has an axial passage 20 communicating by means of cross-passages 21 with the rear steam space 17. The stem 19 terminates at its outer end in a conical or truncate tip 22 which for convenience of manufacture is made separate from the stem 19 and is thereafter secured to the stem 19 as by means of screw threads. The conical tip 22 has a continuation of the axial passage 20 so that steam from the chamber 17 may pass through the openings 21 and 20 out through the end or tip 22 to the atmosphere, this passage being always open. The steam space 17 and the oil space 18 are maintained separate by means of the asbestos packing 23 contained in the counterbore of the casing. This packing is held in place by means of a threaded nut 24 which may be removed by means of a spanner wrench or the like. The rear end of the steam space 17 is closed by means of a packing 25 secured between the nut 26 and the nipple 27 which, for convenience in manufacture, is mounted upon a separate part 28 and so that access may readily be had to the packing 23. The stem 19 is provided at its rear end with the hand wheel 29 and at its front end it is screw-threaded into the nozzle or jet 30 which is secured to the wall between the steam space 16 and the oil space 18. The conical tip 22 on the stem 19 coöperates with the outer end of the jet 30 to form a needle valve for the oil entering from the oil extension 11. The threaded portion of the stem 19 has a number of longitudinal grooves 31 cut therein to allow the passage of oil from the space 18 to the space between the tip 22 and the jet 30. The oil passes out between the tip 22 and the jet 30 in an annular or cylindrical spray, its velocity depending upon the velocity with which the jet is operating. The front end of the casing 15 has an open hole low end into which is screw-threaded the nozzle 32 which coöperates with the jet 30 to define a passage for steam from the space 16 to the outside. The nozzle 32 is provided with projecting ears 33 serving to adjust the same and to indicate the adjustment made.

A lock nut 34 serves to maintain the setting of the nozzle 32. The steam passage 20 is always open and the steam thereto is controlled only by the angle valve 6 in the connection between the nozzle and the steam main.

The passage between the jet 30 and the nozzle 32 can be adjusted by turning the nozzle 32 so as to screw the same in the desired direction. The amount of oil discharged is

controlled by the adjustment of the stem 19 whereby the passage between the jet 30 and the conical tip 22 is increased or decreased. It will be noted that the stem 19 is supported as near as possible to the end which forms the needle valve so as to secure certainty and reliability of action and to prevent eccentricity of the needle valve. After the screw threads have been used for some time they tend to become slightly worn. In devices of the prior art where the spindle is supported from the rear end, the wearing of the threads has produced eccentricity of the passageway and unsatisfactory operation of the burner nozzle. The nozzle is made so that it can very readily be taken apart for cleaning or for renewing the packing. It will be noted that the central spindle 19 is reduced at its inner end so that the spindle may be readily withdrawn through the packings 23 and 25 without catching on the same. When the steam passage between the nozzle 32 and the jet 30 is cut off the oil issuing from the burner nozzle is projected more nearly in a straight line in a longer or thinner flame. When the steam passage between the nozzle 32 and the jet 30 is open the steam forms an outer envelop around the oil space which tends to break up the same into finer particles and project the same in greater volume laterally along the path. The outer envelop of steam issuing between the nozzle 32 and the jet 30 tends at first to compress the inner core of oil and steam due to the kinetic energy of the particles, but as this point is passed, that is the point where the kinetic energy is changed into pressure, the issuing gases or vapors expand very quickly thus forming a large volume of flame adjacent the burner. It is to be noted that during the normal operation of atomizing oil for burning the same that the tip 22 of the spindle 19 projects through the jet 30 and beyond the nozzle 32 so that the steam pressure from the chamber 16 does not create a back pressure tending to prevent flow of the oil. When the nozzle is employed for blowing air and steam through the induction tube 13 the oil passage is shut off by closing the needle valve and also by closing the valve 6 in the connection between the burner jet and the oil supply main. It can then be seen that steam only will issue from the nozzle and will act as an ejector forcing air and steam through the induction tube 13.

As above explained the passage 20 is open at all times and is controlled only by the angle valve 6 in the steam connection. The passage between the jet 30 and the nozzle 32 may be controlled by rotation of the nozzle 32 so that more or less steam is discharged from this passage. The amount of oil discharged is, as above explained, controlled by the needle valve.

While I have described my invention in

connection with the specific details of a particular embodiment, I do not intend thereby that the invention should be construed as being limited to any of these details except 5 as the same may appear in the appended claims. It is obvious to those skilled in the art that numerous modifications and variations may be made without departing from the spirit and scope of the invention.

10 What I claim as new and desire to secure by Letters Patent is as follows:

1. In combination, a pair of supply mains comprising a feed pipe and an oil pipe lying parallel to each other and in a horizontal 15 plane, a burner nozzle lying at substantially right angles to said supply mains, a vertical pipe nipple for each of said mains, angle valves having vertical valve stems connected to said nipples, pipe elbows joined to said 20 nozzle and flexible metallic tubes connecting said elbows and said valves, said elbows joining said nozzle on opposite sides.

2. In combination, a burner shell having a rear and forward steam chamber and an 25 oil chamber between them, and a needle valve having a central axial passage for steam from the rear steam chamber, packing means engaging said valve between said rear steam chamber and the oil chamber,

30 a jet providing a co-axial passage for oil, said valve controlling said oil passage, said valve being supported in its central position in said jet at the nozzle side of the oil chamber, said shell having a passageway exterior 35 of said jet for said other steam chamber.

3. In combination a burner nozzle casting having two steam chambers and one oil chamber therein, a central spindle through said chambers, said spindle having an axial 40 hole communicating with one steam chamber, a threaded support for said spindle, a

conical tip adjacent the threaded part, a jet coöperating with said tip to form a valve, said spindle having grooves communicating with said oil space and the 45 space between the tip and the jet, and means for supplying steam and oil to said steam and oil chambers respectively.

4. In a burner nozzle, a casing having two steam chambers and an oil chamber 50 therebetween, a central spindle passing through said chambers, said spindle having an axial hole communicating with one of said steam chambers, a threaded support for said spindle, a conical tip adjacent the 55 threaded part, a jet coöperating with said tip to form a valve, said spindle having grooves communicating with said oil space and the space between the tip and the jet, a nozzle surrounding the jet and communicating with the other steam chamber, said nozzle being relatively adjustable with respect to said jet to control the size of the steam passage therebetween, said nozzle and said valve being independently adjust- 60 able.

5. In a device of the class described, a body portion having steam chambers and an oil chamber, a central hollow spindle passing axially through said body, said 70 spindle having a separable conical tip screwed upon its inner end, a threaded portion immediately adjacent said tip and a portion of larger diameter back of said threaded portion and packing means engaging said portion of larger diameter.

In witness whereof, I hereunto subscribe my name this 6 day of March, A. D. 1915.

GRAFTON E. LUCE.
